UNITED STATES PATENT OFFICE.

ELIHU LIPPITT, OF GRAND RAPIDS, MICHIGAN, ASSIGNOR TO GRAND RAPIDS UNDER-WEAR COMPANY, OF GRAND RAPIDS, MICHIGAN, A CORPORATION OF MICHIGAN.

PATTERN DRUM AND CHAIN FOR KNITTING-MACHINES.

1,223,811.

Specification of Letters Patent. Patented Apr. 24, 1917.

Application filed January 18, 1915. Serial No. 2,926.

To all whom it may concern:

Be it known that I, ELIHU LIPPITT, a citizen of the United States of America, residing at Grand Rapids, in the county of Kent 5 and State of Michigan, have invented certain new and useful Improvements in Pattern Drums and Chains for Knitting-Machines; and I do hereby declare the following to be a full, clear, and exact description 10 of the invention, such as will enable others skilled in the art to which it appertains to make and use the same.

This invention relates to pattern drum and chain constructions for knitting machines, it being the object and purpose of this invention to provide a drum capable of receiving and operating a pattern chain of indefinite length and especially to provide a chain which may be used with said drum 20 and which may be extended to any desired length whereby a pattern for a knitted fabric may be had not limiting the length of the fabric to any prescribed extent. A further object and purpose of the invention is to 25 provide a special construction of link in the pattern chain which may be quickly and easily attached to, or detached from other links whereby if it is desired at any time to change the pattern, all that is necessary 30 is to remove the required links and insert in their stead others corresponding to the desired pattern. A further object of the invention is to provide means for securing these links together against accidental 35 placement. To these ends I have constructed the drum and chain illustrated in the accompanying drawings, in which;

Figure 1 is a vertical section taken through a knitting machine and illustrating the application of the drum and chain to said machine, only such parts of the knitting machine proper being shown as are necessary to show the application of said drum and chain to the machine.

Fig. 2 is an end view of the drum and chain mounted thereon.

Fig. 3 is a front elevation of the chain.

Fig. 4 shows in side elevation one of the links which are used to make up the completed chain.

Fig. 5 shows two of the links connected

end to end and also illustrates different types of links than that shown in Fig. 4; while, 55

Fig. 6 shows a still further modification in the shape of the links.

Like reference characters refer to like parts throughout the several views of the drawings.

The pattern drum 1 is mounted for rotation a short distance below the needle bed 2 of the knitting machine, said bed carrying a plurality of needles 3 which at their lower ends rest on jacks 4, each jack being provided with a downwardly extending projection 5 passing through the bed 2 and extending toward the pattern drum. The knitting machine as a whole is designated by reference character 6 but only these parts which have particular reference to the pattern drum and chain are specifically noted. 70

A plurality of grooves 7 are formed lengthwise of the drum and spaced equal distances apart around the circumference of the drum. The pattern chain is made up of a large number of links of different shapes, 75 certain links illustrated at 8 being known as "blanks," while other of the links on their outer edges have integral projections 9 extending farther outward than the outer edges of the blanks 8. The projections 9 may be of various lengths as shown in Figs. 4, 5 and 6 extending either the entire working length of the link or merely a fraction thereof. In practice, with each reciprocatory motion of a cam member which actuates needles in a needle bed, as will be fully understood by those skilled in the art of knitting, it is designed that the drum shall be given a movement equal to one-sixth of the distance between each of the grooves 7 and accordingly each of the projections 9 in length are equal to some multiple of one-sixth of the entire working length of a link. With other designs of machines a different fractional part may be used, the invention 95 not being limited in any manner to the specific relations described.

Each link at one end is formed with an integral rounded head or ball 10 and at its other end with a similarly shaped socket 11 whereby a plurality of the links may be fastened together end to end by merely placing

the ball at the end of one link in the socket at the end of another link. Each link also has an integral projection or tooth 12 on its underside and is further provided with 5 an opening 13 substantially midway between its ends.

In building the chain a plurality of links are attached together end to end to any desired or required length, forming an end- 10 less series of links and there may be placed in this series of links any type of link desired, either the blanks 8 or links having projections 9 of greater or less length. A plurality of these endless series of links 15 are then located side by side with the openings 13 thereof in alinement and adapted to receive a rod 14 therethrough which will tie all of the links lying side by side together. The ends of the rod 14 may be 20 headed over to secure the links in such position. There are of course, various ways in which the entire chain may be made up but when completed it will consist of a plurality of endless series of links lying side by side 25 with the openings 13 of the adjacent links in alinement and receiving a tie rod 14.

The width of a link is equal to the distance that the needles 3 are spaced apart, and the width of the completed chain is 30 equal to the length of the pattern drum which lies directly beneath the needle bed, there being an endless series of links for each needle. As the drum rotates step by step the chain will be moved correspondingly, it being understood that the grooves 35 7 of the drum receive the projections or teeth 12 of the links, thereby turning the chain simultaneously with the drum. When any link is a blank the jack 4 will not be 40 elevated and the needle 3 above said jack will remain in lower position, but when any link having a projection 9 thereon comes underneath its associated needle of the needle bed, the projecting portions 5 of the 45 jack will ride on the projections 9 of the link and will be elevated, thereby elevating the associated needle 3 into position to be actuated as the knitting machine is operated. It will be evident that by properly 50 placing the various kinds of links, any pattern may be produced. It is also evident that the pattern chain is not limited in length but may be extended indefinitely so as to produce a fabric of practically in- 55 definite length, and of continuously varied pattern, if desired, the entire length thereof, it not being necessary to repeat the pattern upon the completion of a revolution of drum 1 as heretofore. The links being con- 60 nected by the ball and socket arrangement as described are easily attached together and may be readily detached, being held, however, against accidental displacement in the machine by reason of the fact that a

large number of links are tied together side 65 by side by means of the rods 14 and for any disconnection to take place between two links, it is necessary to move the body of links corresponding to the entire width of the chain which is a practical impossibility. 70

A pattern chain of this construction has great utility and may be quickly and easily constructed and assembled and when any link or links become worn, broken or in any other manner useless, it can be very easily 75 repaired without the necessity of throwing away the entire chain or an entire connected series of links.

Without limiting myself to details of construction, I claim:

1. A pattern chain for knitting machines comprised of a plurality of flat links having their ends detachably connected together to form an endless series, a plurality of said endless series of links located side 85 by side, with the sides of the links in contact throughout the entire length thereof and means connecting the corresponding contacting links of the different series together, substantially as described. 90

2. A pattern chain for knitting machines comprised of a plurality of flat links having ends detachably connected together to form an endless series of links, a plurality of said endless series of links located side 95 by side, and rods passing through the corresponding contacting links of the different series serving to connect said links together, substantially as described.

3. A pattern chain for knitting machines 100 comprised of a plurality of links, each formed with a rounded head at one end and with a socket at the other end, said head and socket being in alinement, said links being detachably connected end to 105 end to form an endless series, the socket of one link receiving the head of an adjacent link, a plurality of said endless series of links located side by side, and means connecting the contacting links of the different 110 series of links together, substantially as described.

4. A link for pattern chains formed from a flat piece of metal having a rounded head 115 at one end and a socket at the opposite end, said head and socket being in alinement, and a tooth projecting at one edge of the link between the ends thereof.

5. A link for pattern chains formed from a flat piece of metal having a rounded head 120 at one end and a socket at the opposite end, said head and socket being in alinement, a tooth at one edge between the ends of the link and an integral projection at the opposite edge of the link, substantially as de- 125 scribed.

6. A link for pattern chains formed from a flat piece of metal having a rounded head

at one end, a socket at the opposite end, said head and socket being in alinement and an opening in the body of the link between the ends thereof, a tooth at one edge between the ends of the link and a projection at the opposite edge of the link, substantially as described.

In testimony whereof I affix my signature in presence of two witnesses.

ELIHU LIPPITT.
